Patented Dec. 6, 1966

206,403

FOOD CUTTER

Joachim R. Beltram, Livingston, N.J., assignor to International Edge Tool Co., Newark, N.J., a corporation of New Jersey

Filed June 6, 1966, Ser. No. 2,587

Term of patent 14 years

(Cl. D55—1)

FIGURE 1 is a top plan view of a food cutter of the present design.

FIGURE 2 is a front elevational view of the food cutter.

FIGURE 3 is a rear elevational view of the food cutter.

FIGURE 4 is a bottom view of the food cutter.

FIGURE 5 is an end view of the food cutter as viewed from the right in FIGURE 1.

FIGURE 6 is an end view of the food cutter as viewed from the left in FIGURE 1.

FIGURE 7 is a cross-sectional view taken along lines 7—7 of FIGURE 2.

I claim:

The ornamental design for a food cutter, substantially as shown.
